UNITED STATES PATENT OFFICE

WILLIAM FERGUSON, OF PHILADELPHIA, PENNSYLVANIA, ASSIGNOR TO NATIONAL AIROIL BURNER COMPANY, INCORPORATED, A CORPORATION OF DELAWARE

GAS AND OIL BURNER

Application filed February 5, 1929. Serial No. 337,570.

The invention relates to gas and oil burners. The object is to provide a combination gas and oil burning unit, adapted to burn either oil, or gas, or both simultaneously.

10 The invention comprises means whereby the heat derived from the burning of either medium may be utilized for facilitating the combustion of the other medium, and whereby the heat derived from the combustion of both mediums will facilitate the combustion of each medium.

15 The invention is especially applicable in the distillation of oil, in which case the combustion of oil, is first used to heat the still and, when the still is on stream, the gas derived therefrom may be ignited and burned and the combustion of oil may be discontinued, as long as the gas derived from the still is sufficient to continue the distilling operation. 20 Where the gas is insufficient, oil may also be burned to supplement the gas flame to secure or maintain the required temperature.

25 In other words the fuel oil burner can be operated at the same time the gas burner is operated, depending upon the quantity of each grade of fuel available.

30 The gas which is burned in this type of equipment, when used in connection with oil distillation, is a by-product from the various cracking processes used to manufacture a cracked gasoline from cheaper grades of petroleum fractions, such as the so-called gas oils, fuel oil residue etc. The quantity of this 35 gas available at the refinery varies with the degree of cracking that the material undergoes, and with the origin of the crude.

40 This gas contains a high percentage of sulphur which, under high temperature, decomposes iron or brass into sulphites, thus resulting in clogging any small orifices through which it may pass. The use of a refractory burner tip has been found to be effective means for overcoming this action.

45 As the gas used in this improved burner is a by-product, the said device is adapted to operate with maximum economy and efficiency.

50 The invention also comprises improvements in construction and arrangement.

Referring to the drawings, which illustrate merely by way of example, a suitable embodiment of my invention,

Fig. 1 is a vertical section.

Fig. 2 is an elevation of parts to the right 55 of line 2, 3.

Fig. 3 is an elevation of parts to the left of the line 2, 3.

Fig. 4 is a sectional detail, on an enlarged scale, of the gas burner ring and tip. 60

Fig. 5 is a front elevation, on an enlarged scale, of the oil burner tip.

Fig. 6 is an enlarged fragmentary elevation of the gas ring.

Similar numerals refer to similar parts 65 throughout the several views.

The oil burner element 6 is of standard type, with the addition of tip 7 with orifices 8, so arranged as to produce a hollow cone flame; the shape of which flame corresponds 70 approximately with the flare of passage 9 of the refractory body or formation 10. The passage 9 leads from the oil burner to the combustion chamber 30.

The burner element 6 is connected by pipe 75 11 with the oil supply, controlled by oil valve 12, and by the pipe 13 with steam supply, controlled by the steam valve 14; both valves 12 and 14 are provided with indicating scales 15 and 16, as shown. The oil burning unit is supported by the pipes 11 and 13, which in turn are supported in the frame structure 17 within the cylindrical body 18 of the air valve 19. The cylinder 18 is slidably supported in the cylindrical formation 85 or bracket 20, forming part of the front casting 21 of the furnace. The frame structure 17 is secured in stationary relationship with the stationary pipes 11 and 13 or by other suitable means.

90 The valve 19 is secured to one end of cylinder 18, to the other end of which cylinder is secured the head or hand piece 23 for manual operation, so that the cylinder 18 may be moved horizontally to bring the valve 19 into and out of position shown by the dotted line, to close or open the flaring opening 24 in the refractory formation 10, by which means the amount of air delivered from chamber 25 to the oil burner may be regulated, thus sup- 95 100

plying the various quantities of combustion air required at different capacities.

The gas ring 26 is supported on the four one inch pipes 27, slidably mounted in collared formations 28 of the front casting 21. One or more of these pipes, preferably two oppositely disposed pipes, may be connected with the gas header 29. This gas ring is circular in form, and is provided, in its face 10 toward the combustion chamber, with a plurality of orifices, in which are provided orificed tips 36 of refractory material. These burner tips are closely and equally spaced around the ring 26, and register with the 15 annular channel or space 31 formed between the cylindrical body 10 of refractory material and the surrounding concentric body or cylinder 32 of refractory material. The object of the large number of gas jets is in 20 accordance with the accepted practice that gas, to be burned quickly and efficiently, must be broken up into a large number of fine streams so that intimate contact and entrainment between gas and combustion air 25 is possible.

The annular channel 31, which also delivers to the combustion chamber, is slightly tapering, as for example, it may measure about two and one-half inches at the receiving or gas ring end, and about two inches at the discharge or combustion chamber end. The two bodies 10 and 32 are spaced apart by the spacing blocks 33 seated in oppositely disposed recesses in said bodies. The outer 35 body 32 is supported in the surrounding mason work forming a wall of the combustion chamber.

An adjustable natural draft air door 34 is provided in the lower part of casting 21 for admitting air to chamber 25.

It will be noted that the inner formation or body 10 of refractory material forms a venturi, that is, a passage flaring at each end and having a contracted throat between the two 45 ends.

An important feature of the design is that the casting supporting the burner parts of the unit, is largely protected from the radiant heat of the furnace by the refractory blocks interposed between it and the furnace and any slight heating that may take place is to a substantial extent compensated for by the combustion air passing across it.

In operation:

55 The oil burner is usually operated first, until the device is on stream and gas is generated in the still. This gas is delivered to the gas ring and the gas burner is then brought into operation.

60 If the amount of gas supplied is sufficient to maintain the required temperature, then the oil burner may be shut off.

The jets of gas are directed through the channel 31, between the refractory blocks 10 and 32, and in so doing the mixture of gas

and air is made more complete and ignition is secured by means of the refractory blocks radiating heat to the mixture.

Usually while burning gas, the damper disc or valve 19 is in the closing position and the air for combustion is supplied from chamber 25 and drawn in by the inductive action of the gas projected into the annular channel 31 between the blocks 10 and 32. The distance of the gas tips 36 from channel 31 will be a factor in controlling said inductive action. In some cases the valve 19 may be opened to admit some air through the passage 9, and thus change the flame characteristic. This air is considered a secondary air and tends to increase the luminosity of the burning gas and consequently the heat radiating properties.

Generally speaking, this burner would not be considered a pre-mixing type, but strictly speaking, it is one, because the gas is supplied to the ring under a pressure of from 3 to 15 pounds, and, issuing through the orifices, it has a velocity which averages 800 ft. per second, and the flame, resulting from a mixture of gas is equal to 10% of the volume of air, has a flame propagation of 62 ft. per second. It will therefore be evident that the gas streams have several times the velocity of the flame needed. Therefore, between the time 45 that the gas leaves the burner tips and the time that it is ignited, it goes through a pre-mixing period, thus no "flare back" can occur.

As a result of this method of burning gas, 500 a bluish flame is obtained, which corresponds very closely to the flame obtained with the ideal pre-mixing arrangement, or in some cases it may be slightly tinged with red, and if so desired, it can be made somewhat luminous by admitting some air past the damper 19 as previously stated. The arrangement is 105 very flexible as regards the flame characteristics.

In order to secure the required capacity, at 110 the desired pressure, tips of different capacity are used in the gas ring. For example, when it is desired to burn 8000 cu. ft. of gas per hour at 10 lbs. pressure 40 tips each having a capacity of 200 cu. ft. of gas per hour 115 at 10 lbs. pressure may be used, or where more rapid burning or oxidization of the gas is desired, 53 tips, each having a capacity of approximately 150 cu. ft. per hour, at 10 lbs. pressure, may be used.

As above stated, the fuel oil burner can be used at the same time gas is used, or separately, depending upon the quantity of each grade of fuel available.

What I claim is:

1. In a gas and oil burner, the combination of means forming a combustion chamber, two concentric cylindrical refractory formations, the inner formation supported in spaced relationship within the outer cylindrical forma- 130

tion and forming therewith an annular passage to the combustion chamber, the inner formation providing a centrally located passage to the combustion chamber, an oil burner projecting into and delivering to the central passage, and a circular gas burner having a plurality of vents delivering to the annular passage.

2. In a gas and oil burner, the combination of means forming a combustion chamber, two concentric cylindrical refractory formations, the inner formation supported in spaced relationship within the outer cylindrical formation and forming therewith an annular passage to the combustion chamber, the inner formation providing a centrally located passage to the combustion chamber, an oil burner projecting into and delivering to the central passage, a circular gas burner having a plurality of vents delivering to the annular passage, and means associated with said passages for controlling the amounts of primary and secondary air for the gas combustion.

3. In a gas and oil burner, the combination of means forming a combustion chamber, two concentric cylindrical refractory formations, the outer formation supported in the wall of the combustion chamber, the inner formation supported, by parallel longitudinally extending spacing elements, in spaced relationship within the outer cylindrical formation and forming therewith an annular passage to the combustion chamber, the inner formation providing a centrally located passage to the combustion chamber, an oil burner projecting into and delivering to the central passage, and a circular gas burner delivering to the annular passage.

4. In a gas and oil burner, the combination of means forming a combustion chamber, two concentric cylindrical refractory formations, the inner formation supported in spaced relationship within the outer cylindrical formation and forming therewith an annular passage to the combustion chamber, the inner formation providing a centrally located passage to the combustion chamber, an oil burner projecting into and delivering to the central passage, a circular gas burner delivering to the annular passage, means for supplying air to said passages and adjustable means for the control thereof whereby the relation of the air supply through said passages may be changed as required.

5. In a gas and oil burner, the combination of means forming a combustion chamber, two concentric cylindrical refractory formations, the inner formation supported in spaced relationship within the outer cylindrical formation and forming therewith an annular passage to the combustion chamber, the inner formation providing a centrally located passage to the combustion chamber, an oil burner projecting into and delivering to the central passage, a circular gas burner having a plu-

rality of vents delivering to the annular passage, an air chamber in communication with said passages, adjustable means for controlling the admission of air to said chamber as an additional adjustable air control between said chamber and one of the passages.

6. In a gas and oil burner, the combination of means forming a combustion chamber, two concentric cylindrical refractory formations, the inner formation supported in spaced relationship within the outer cylindrical formation and forming therewith an annular passage to the combustion chamber, the inner formation providing a centrally located passage to the combustion chamber, an oil burner projecting into and delivering to the central passage, a circular gas burner having a plurality of vents delivering to the annular passage, and means, comprising interchangeable burner-tips for varying the capacity and pressure of the gas burner.

7. In a gas and oil burner, the combination of means forming a combustion chamber, two concentric cylindrical refractory formations, the inner formation supported in spaced relationship within the outer cylindrical formation and forming therewith an annular passage to the combustion chamber, the inner formation providing a centrally located passage to the combustion chamber, an oil burner projecting into and delivering to the central passage, a circular gas burner having a plurality of vents delivering to the annular passage, the oil burner provided with a burner-tip having a beveled end and a circle of vents so directed as to secure a hollow flaring discharge of atomized fuel.
